UNITED STATES PATENT OFFICE.

REUBEN HOFFHEINS, OF DOVER, PENNSYLVANIA.

IMPROVEMENT IN HARVESTERS.

Specification forming part of Letters Patent No. 40,481, dated November 3, 1863.

To all whom it may concern:

Be it known that I, REUBEN HOFFHEINS, of Dover, in the county of York and State of Pennsylvania, have invented certain new and useful Improvements in Harvesters; and I do hereby declare the following to be a full and exact description of the same, reference being had to the accompanying drawings, making part of this specification, in which—

Figure 1 is a front perspective view of my improved machine as arranged for cutting grain. Fig. 2 is a rear perspective view of the same in the form of a mower. Fig. 3 is a side elevation of the same as arranged for transportation. Fig. 4 is a perspective view of the main frame detached. Fig. 5 is a plan of the top of the post on which the rake is mounted.

Similar letters of reference indicate corresponding parts in the several views.

My present improvements consist, first, in a peculiar construction and combination of frame-gearing and double driving-wheels, for purposes hereininafter to be explained; second, in a device for affording protection to the main crank-shaft and strengthening the main frame; third, in the use of a movable tongue which may be secured in various positions to adapt it for various uses of the machine; fourth, in a device for permitting the finger-beam to turn freely on its own axis.

In order that others skilled in the art to which my invention appertains may be enabled to fully understand and use the same, I will proceed to describe its construction and operation.

The main frame A A is cast in one piece, in the form represented in Fig. 4, the ends being left disconnected to facilitate casting and to reduce the weight.

B B' are two driving-wheels, adapted to turn on the axle C, but each furnished with a pawl, b, taking into a ratchet-wheel, b', on the axle, so as to impart rotation thereto when the wheel is turning forward.

b² represents a spring bearing against the square heel of the pawl b to hold it either in or out of gear in whichever position it may be set.

C' is the main gear-wheel on the axle C, which gears with a pinion, d, on the transverse shaft D, which carries at its other end a bevel-cog wheel, D', gearing with a bevel-pinion, e, on the crank-shaft E.

E' is the crank-wheel, mounted on the rear end of the shaft E and imparting motion to the cutter F by means of a pitman, f, which is provided with a swivel, f', formed of a screw-thread and nut to permit the rolling of the finger-beam without straining or binding the cutter.

a represents a flange cast upon the main frame for the purpose of imparting additional strength thereto, and also protecting the crank-shaft E.

G is the finger-beam, attached at its respective ends to the inner shoe, H, and the outer shoe or divider, H'. The inner shoe, H, is pivoted by its center, at h, to the drag-bar I by a universal joint and at its respective ends to guides h' h', which work in vertical dovetail slots formed in pendants i i on the drag-bar in such a manner as to brace the beam horizontally, while permitting it to turn freely on its axis, either for the purpose of conforming to the undulations of the ground, to rise over an obstruction, or to be turned up edgewise and carried on the machine in manner represented in Fig. 3, the point of the divider H' resting in a staple, k, in the side of the tongue K. The tongue is attached to the main frame by means of two bolts, k', passing through it and through notches or holes j j' or j' j at one side of or near the center of the frame, so as to permit the adjustment of the said tongue to a position between the wheels for cutting grain, as illustrated in Fig. 1, or on the outside for cutting grass, as illustrated in Fig. 2. In either position an extension, K', from the tongue affords means for supporting the inner end of the finger-beam. This is effected in the illustration given in Fig. 1 by a chain, J, rising from the outer end of a rigid arm, J', which projects inward from the beam, and in the illustration shown in Fig. 2 by a chain, J², attached at its lower end to a staple, h², in the lateral stay-rod, H², and at its upper end to a segment-lever, M, fulcrumed at m on the rear end of the tongue, so that by raising the said lever the heel of the beam may be raised to any required height. A rack, M', holds the lever M in any position in which it may be placed.

H² represents a track-clearer pivoted in front to the rear of the divider or outer shoe, H'. On the rear end of the inner shoe is formed a lug, h⁴, for the attachment of the inner side of

the segmental grain-platform P. The said platform is secured to the finger-beam, at suitable intervals, by straps O and bolts o.

N represents a caster-wheel secured adjustably to the outer edge of the platform, and employed to carry the same at any desired height.

Q represents a grain-fender, of sheet iron, pivoted in front upon the cast-iron divider H', and adjustable in height at its rear end by a bolt placed in either of the holes q. On the inner side of the grain-platform, near the heel of the finger-beam, is firmly mounted a post, R, which may incline over toward the main frame, as shown in Fig. 1. The said post is braced by stay-rods r r r, the respective lower ends of which may be bolted to the platform, the front of the shoe H, and the outer end of the rigid arm J', so as to secure the post in rigid connection with the platform and cause it to follow all the motions of the latter. The post R is provided at its upper end with a cogged segment, S, and a segmental guideway, s', (see Fig. 5,) by which the revolving rakes are turned and held in the required positions, as will be presently explained.

T is an inverted crown-wheel, provided with a vertical shaft, which is journaled in a box on the upper part of the post R. Rotation is communicated to the crown-wheel T by an extensible tumbling-shaft, U U', of square form, made in two parts, sliding one within the other, so as to assume any length which the positions of the parts may require, and work equally well in any position. The said extensible tumbling-shaft is connected at its respective ends by universal joints to pinions u' u², the first, u', mounted upon the main frame and gearing with a pinion, u³, on the axle C, and the second, u², mounted on the post R and gearing with the crown-wheel T.

The rake or reel arms V V' are mounted in pairs upon the ends of horizontal shafts v v', journaled at right angles across the top or back of the inverted crown-wheel T. At the junction of each of the rake or reel arms with the shafts v v' is secured a cogged segment, v², adapted to gear with the fixed cogged segment S, and in passing over the same to turn the reel or rake on that side to its inverted and elevated position, in which position it is held during about one-fourth of its revolution by a rigid arm, v³, resting on the segmental guideway s'; and it will be apparent that the corresponding reel or rake arm, being rigidly secured to the opposite end of the same shaft, will be held in its lower or working position during the same period.

W represents the driver's seat.

Operation: For cutting grain the parts are arranged as shown in Fig. 1. The successive rake and reel arms, descending in front of the finger-beam, deflect the grain backward toward the cutters in customary manner, and the rakes remove the cut grain in compact gavels from the platform.

The use of the rigid arm J', projecting inward from the finger-beam and supporting the latter and the attached platform from the rear of the tongue, diminishes the abruptness of the motions of the cutting apparatus and platform without restricting their freedom in conforming to undulations of the ground.

The peculiar devices for transmitting motion to the rake adapt it to act equally well at any height or angle of the platform.

In mowing, the cutters are left perfectly free, but may be raised or lowered by the operator in the manner already explained, the tongue K being transferred to a position on the outside of the wheel B'.

The peculiar construction and attachment of the inner shoe adapt the finger-beam to roll freely on its axis in use, or to be turned over on its edge and folded compactly against the frame, as illustrated in Fig. 3, to adapt the machine to be moved from place to place.

The pawl or ratchet connection between the driving-wheels and their axle adapt the machine to be turned or backed with perfect freedom, and also afford ready means for throwing the entire machinery out of gear, which is effected by raising the pawls out of the ratchets, where they will be held by the springs b².

The cutting apparatus may be thrown out of gear by moving the transverse shaft D longitudinally by a lever, D², and providing it with a pin, d², which, in one position of the shaft, will fit in a recess in the hub of the wheel, so as to impart rotation thereto, and in the other position will permit the shaft to turn independently of the wheel. This lever may be moved by the hand or foot of the driver.

Having thus described my invention, what I claim as new therein, and desire to secure by Letters Patent, is—

1. The main frame and gear-frame A A, constructed as described, open at each end, when used in combination with shafts, gearing, and double driving-wheels, arranged and operating substantially as and for the purposes specified.

2. The flange a, cast or formed upon the gear-frame for the combined purposes of strengthening the latter and protecting the crank-shaft E, as hereinbefore explained.

3. The movable tongue K, adapted to be attached to the frame on either side of the wheel B', and employed to support or raise the inner end of the beam.

4. Attaching the shoe to the drag-bar by a transverse swivel-joint to permit the finger-beam to turn on its axis to elevate or depress the points of the fingers, or to fold the beam against the frame for transportation when combined with bracing-guides h', substantially as herein described.

REUBEN HOFFHEINS.
